UNITED STATES PATENT OFFICE

2,186,313

AUTOMATIC SWITCH AS USED IN TELEPHONE OR LIKE SYSTEMS

Denis Wright, Liverpool, England, assignor to
Associated Telephone & Telegraph Company,
Chicago, Ill., a corporation of Delaware

Application March 19, 1938, Serial No. 196,825
In Great Britain March 30, 1937

6 Claims. (CL. 200—166)

The present invention relates to automatic switches as used in telephone or like systems and is more particularly concerned with mounting arrangements for switches of the two-directional type arranged to have longitudinal and rotary motion.

In such switches as is well known the controlling relays, driving mechanism and wipers of each switch are generally provided as a single unit which is readily detachable from the support (commonly referred to as a switch "shelf") upon which it is mounted. The multiply-connected contact banks are fixed to the shelf in such a position as to be accessible to the wipers of their respective switches when the switches are mounted, and there is accordingly the danger that when such switches are replaced in position, the wipers will become damaged by engagement with the bank if they have been left in an off-normal position.

This is particularly so in the case of switches which are mounted by means of an arrangement of the type described in the patent to Saxby, No. 2,067,246 in which the action of mounting the switch involves a movement of rotation followed by one of translation, for it is during this latter movement that the wipers are likely to be damaged owing to their being brushed across the bank in a direction at right angles to the rows of contacts.

The object of the invention therefore is to provide an improved guarding device suitable for attachment to switches of the above type which will prevent their reengagement with the bank if their wipers are in an off-normal position.

According to the invention a movable member adapted to co-operate with the switch wipers is so arranged as to offer resistance to the mounting of the switch on its support if the wipers are in such a position that they would be likely to suffer damage by such action.

The invention will be better understood from the following description of one method of carrying it into effect reference being had to the accompanying drawing comprising Figs. 1 and 2, which show the guarding device applied to the two-directional switch and mounting arrangement disclosed in the Saxby patent previously referred to. Fig. 1 is a front perspective view of the lower portion of the switch and bank as it appears when the switch is mounted upon the shelf as described in the Saxby patent. The wipers are shown in their normal position slightly below and to the left of the contact bank; in

this position the wiper carriage is prepared to engage one arm of the pivoted safety catch 13 when the switch is lifted from its mounting. Fig. 2 is a similar view of the switch when removed from the switch shelf, and shows the wipers in an off-normal position to permit rotation of the safety catch. As will be seen from the drawing only sufficient of the constructional details of the switch have been shown as are necessary for describing the application of the invention.

Referring now to Fig. 1 the vertical slots in the side members 10 and 11 engage lugs on opposite sides of the mounting bracket member 12, which is similar to the bracket member 14 shown bolted to the lower contact bank in the above-mentioned patent to Saxby, while the pivoted safety catch 13, which is added in accordance with the invention, bears against the inclined face 14 of the bracket and is thus held slightly clear of the lower wiper assembly 15. This is the normal position of the safety catch and so long as this position is maintained, as it must be when the switch is correctly mounted, there can be no interference with the operating and releasing movements of the wiper assembly.

When the switch is removed from its mounted position with the wipers still in their normal position, the pivoted safety catch 13 loses the support of the inclined face 14 of the bracket 12 and is then urged by the hairpin spring 16 against the fibre portion of the lower wiper assembly 15. The movement of the safety catch in these circumstances is however very slight, since it is only required to take up the clearance between itself and the wiper assembly and to all intents and purposes the safety catch may be regarded as having been maintained in its normal position.

If however the wiper carriage is moved by hand from its normal position with the switch removed from its mounting, the fibre portion of the lower wiper assembly is raised clear of the safety catch, which swings to the left under the influence of the hairpin spring until it comes up against the side member 10 in which position the tapered end of the catch blocks the opening to the vertical slot in the side member 10. This is the condition illustrated in Fig. 2.

Accordingly if the wiper carriage is left in an off-normal position and an attempt is made to replace the switch in its mounted position on the bracket, the end of the safety catch will foul the lug on the bank contact which would otherwise enter the vertical slot in the side member 10, with the result that the attempted replace-

ment of the switch is prevented and attention is called to the off-normal condition of the wipers.

It therefore becomes necessary for the wipers 5 to be rotated in a clockwise direction to their extreme position from which they fall by gravity and rotate in the reverse direction under spring pressure to their normal position. Towards the end of the rotary release movement 10 the fibre part of the lower wiper assembly comes up against the safety catch which it swings to the right in order to open the slot in the side member 10. The mechanism is now in the correct condition for the replacement of the switch 15 on the supporting bracket, and when this is done, the safety catch rides along the inclined face 14 of the bank bracket and is thus caused to execute a further slight movement to the right in order to produce a clearance between 20 itself and the wiper assembly as is desirable during normal operation.

I claim:

1. In combination, a support, a bank of contacts in fixed relationship to said support, a 25 switch having movable wipers, means for detachably mounting said switch upon said support thereby to place said wipers in operative relationship with said bank of contacts, and means controlled by the position of the wipers to prevent the mounting of said switch upon said support if said wipers are in such a position as to be damaged by said contacts in the mounting 30 of the switch.

2. In a combination as claimed in claim 1, 35 wherein said last means includes a member at times mechanically linked to said wipers when said switch is detached from said support, means controlling said member to prevent the same from being linked to the wipers when said switch 40 is mounted upon said support.

3. A combination as claimed in claim 1, wherein said switch is a two-motion switch whose wipers have a longitudinal movement and a rotary movement.

4. In combination, a support, a bank of contacts in fixed relationship to said support, a switch having movable wipers, means for detachably mounting said switch upon said support thereby to place said wipers in operative relationship with said bank of contacts, said wipers 10 having a normal position, and means for preventing the mounting of said switch upon said support if said wipers are not in said normal position.

5. In a mounting arrangement, a support, a 15 switch, means including a lug and slot combination for detachably mounting said switch upon the support, a member at times blocking said slot when said switch is detached from said support thereby to prevent said switch from 20 being mounted upon said support, movable wipers carried by said switch, and means controlled by the position of said wipers for at other times preventing said member from blocking said slot. 25

6. In a mounting arrangement, a support, a bank of contacts in fixed relationship to said support, a switch having movable wipers, means including a lug and slot combination for detachably mounting said switch upon the support 30 thereby to place said wipers in operative relationship with said bank of contacts, a member controlled in accordance with the position of said wipers when said switch is detached from said support, and means for operating said member 35 to block said slot if said wipers are in such a position as to be damaged by the bank of contacts in the mounting of said switch.

DENIS WRIGHT. 40
